UNITED STATES PATENT OFFICE.

HOWARD D. COLMAN, OF ROCKFORD, ILLINOIS, ASSIGNOR, BY MESNE ASSIGNMENTS,
TO EDGAR S. NETHERCUT, OF EVANSTON, ILLINOIS.

STOPPING AND RESTARTING MECHANISM.

Application filed December 3, 1919. Serial No. 342,259.

To all whom it may concern:

Be it known that I, HOWARD D. COLMAN, a citizen of the United States, residing at Rockford, in the county of Winnebago and 5 State of Illinois, have invented new and useful Improvements in Stopping and Restarting Mechanisms, of which the following is a specification.

This invention has particular, although 10 not exclusive reference to winders of the class in which there is a winder-tending mechanism arranged to travel around the winder and operate upon the winding units. A winder of this type is shown in Patent 15 No. 1,267,977, dated May 28, 1918. The winder-tending mechanism disclosed in said patent is arranged to be automatically stopped upon the completion of each round trip and to be automatically restarted after 20 an idle period of predetermined length. The winder-tending mechanism is stopped and restarted by means acting upon switches included in the electric circuits that furnish current to the motor of the winder-tending 25 mechanism.

The object of the present invention is to provide stopping and restarting means arranged to act upon a clutch that controls the transmission of power from the motor to the 30 mechanism for causing the winder-tending mechanism to travel, the aim being to eliminate the necessity of starting the motor under load since this is apt to produce sparking at the motor brushes which is obviously 35 objectionable because of the resulting increase of fire hazard.

In the accompanying drawings, Figure 1 is an elevation section through a winder showing, in side elevation, winder tending- 40 mechanism and controlling means therefor. Fig. 2 is a fragmentary side elevation of a portion of the controlling means. Fig. 3 is a fragmentary plan view of one end of of the winder showing the winder-tending 45 mechanism at rest at the beginning of a round trip. Fig. 4 is a fragmentary horizontal section on an enlarged scale taken in the plane of line 4—4 of Fig. 8. Fig. 5 is a fragmentary side elevation of the mechanism 50 shown in Fig. 4. Fig. 6 is a fragmentary vertical section on an enlarged scale taken sub-

stantially in the plane of line 6—6 of Fig. 1. Fig. 7 is a fragmentary horizontal section taken in the plane of line 7—7 of Fig. 6. Fig. 8 is a fragmentary vertical section 55 taken on line 8—8 of Fig. 5.

The invention is herein shown as embodied in a machine generally similar to the one disclosed in the before-mentioned Patent No. 1,267,977. Reference may be made to 60 said patent for an understanding of the construction and operation of the mechanism co-operating with those herein illustrated.

The winder-tending mechanism is mounted upon an endless elevated rail 86 65 consisting of two straight parallel portions and semicircular end sections. The carriage or framework of the winder-tending mechanism consists of a base or main section 88 and a depending frame 89 rigidly attached to 70 one end of the base. At one end of the base 88 are two rollers 90 arranged to run upon the rail 86. Adjacent to one of the rollers 90 is a guide roller 91 turning upon a vertical axis and bearing upon an endless guide 75 rail 92. Adjacent to the other roller 90 is a pinion 93 rotating upon a vertical axis and meshing with an endless rack 94 arranged at the outer edge of the rail 86. Guide rollers 95 and 96 run along the inner 80 edge of the rail 86 adjacent to the roller 91 and the pinion 93, respectively. The opposite end of the base 88 is supported upon a roller 97. When the winder-tending mechanism reaches one end of the winder and the 85 rollers 90 pass onto the semicircular rail portion at that end of the machine, the base 88 turns through an arc of 180° as the rollers 90 traverse said semicircular rail section, the roller 97 moving on the curved rail 98 to the 90 other side of the winder framework.

Power to actuate the winder-tending mechanism and to cause said mechanism to travel upon the rail 86 is supplied by an electric motor 103 mounted upon that end of 95 the base 88 which is carried by the roller 97. Power is communicated from the motor 103 to the pinion 93 and the mechanisms that operate on the winder units by means comprising a belt 203 running over a pulley 204 on the armature shaft and over a pulley 205 rotatably mounted on a shaft 206. 207 is a 100

nut on the shaft 206 preventing sidewise displacement of the pulley 205 in one direction. The side of the pulley 205 opposite to the nut 207 is provided with a tapered friction surface 208 adapted to receive a correspondingly tapered friction clutch member 209 fixed upon a sleeve 210. Said sleeve is slidable along the shaft 206, but the shaft is connected to rotate with the sleeve by means of a spline 210^a (Figs. 4 and 8). An expansion spring 211 surrounding the shaft 206 is interposed between the shoulder 212 on said shaft and a flange 213 on the end of the sleeve 210, said spring serving to hold the clutch member 209 normally in engagement with the clutch surface 208.

It is desirable that the winder-tending mechanism shall be ready to operate upon the successive winding units promptly after the bobbins exhaust. The time required to empty a bobbin varies with the amount of yarn thereon. It is therefore desirable that the travel of the winder-tending mechanism shall be subject to control so that it may be varied when changes are made in the character of the yarn being wound. The winder-tending mechanism is therefore arranged to wait at one end of the winder framework after each round trip for such a length of time that the active bobbin of the next unit to be operated upon shall almost certainly be exhausted before the winder-tending mechanism reaches it. The length of the stoppage of the winder-tending mechanism is predetermined in accordance with the maximum length of time necessary to unwind bobbins containing a given size of yarn spun with a given amount of traverse and a given size of spinning ring.

When the winder-tending mechanism has passed the winding units located at one side of the machine, an element carried by the winder-tending mechanism is caused to disengage the clutch member 209 from the pulley 205, thereby suspending the travel of the carriage 88 and stopping the mechanisms for operating upon the units. The element referred to is an arm 700 (Fig. 8) which is fixed upon a horizontal rock shaft 701 mounted on the carriage 88. The arm 700 lies in contact with a pin 702 carried by a fork 703. Said fork is supported in the framework of the winder-tending mechanism for pivotal movement upon the axis 704 and carries two studs 705 that lie at the side of the flange 213 opposite to that engaged by the expansion spring 211.

Fixed to the shaft 701 is a downwardly extending arm 706. In the travel of the carriage 88 the lower end of the arm 706 is carried into contact with one end of a horizontal bar 707 (Fig. 2) which is supported upon parallel motion arms 708 and 709. The

arm 708 is pivoted on a bracket 710 attached to the stationary framework of the winder. The arm 709 is fixed upon a rock shaft 711 which is mounted in suitable brackets in the winder framework. A contractile spring 712 acting upon the arm 708 normally holds the bar 707 in position to be engaged by the arm 706, the action of said spring being limited through contact of an arm 713 on the shaft 711 with a stop pin 714. The bar 707 is normally held against movement by means of a pivoted latch 715 engaging the arm 713; consequently, when the arm 706 strikes the end of the bar 707 the continuing travel of the carriage 88 causes the shaft 701 to turn, thereby throwing out the clutch member 209, the end of the arm 706 sliding along the top of the bar 707 until the movement of the carriage 88 due to momentum ceases.

When the winder-tending mechanism is to be again set in operation, the latch 715 is disengaged from the arm 713, whereupon the spring 211, acting through the arm 706, overcomes the spring 712, and moves the bar 707 upon the arms 708 and 709 downwardly until the arm 706 again assumes its normal position. As the arm 706 moves into such position, the spring 211 throws in the clutch member 209. The means for disengaging the latch 715 from the arm 713 will next be described.

A shaft 716 (Fig. 6) is continuously driven in any suitable manner, as by being directly connected to one of the cam drum shafts (not shown) of the winder. On the shaft 716 is fixed a worm 717 that meshes with the worm wheel 718 which is fixed upon a shaft 719. The shaft 719 is supported in a casing 720 which is mounted on the framework of the winder. Fast on the shaft 719 is a worm 721 that meshes with a worm wheel 722 which is fixed upon a sleeve 723. To the lower end of the sleeve 723 is fixed a friction clutch member 724. A coacting friction clutch member 725 is rigidly fixed to one side of a disk 726. An expansion and torsion spring 727 normally holds the friction clutch member 725 pressed against the clutch member 724. One end of the spring 727 is attached to the clutch member 725, while the other end is connected to a normally stationary part. On the periphery of the disk 726 is a cam or lug 728 which is arranged to engage an arm 729 which is fixed upon a rock shaft 730. Upon the opposite ends of the shaft 730 are band wheels 731. Rigid with relation to the arm 729 is an arm 732 which is connected by means of the link 733 with an arm 715^a that is rigid with the latch 715. A contractile spring 735 (Figs. 1 and 6) normally holds the latch 715 and the arm 729 in the position shown in Figs. 2 and 6. It will be

seen that the shaft 716 will rotate the disk 726 relatively slowly, and that engagement of the lug 728 with the arm 729 will cause the latch 715 to be disengaged from the arm 718. When the latch 715 is thrown out as just described, the winder-tending mechanism begins to travel. Shortly thereafter, a roller 736 mounted on the carriage 88 is carried against and depresses an arm 737 (Fig. 1), said arm being pivotally supported in the framework of the winder. Rigid with the arm 737 is an arm 738 which is connected by means of a link 739 to one arm of a lever 740 which is pivoted in the casing 720. The other arm of the lever 740 overlies the upper end of a spindle 741 which is slidably and rotatably mounted in the sleeve 723. The spindle is connected to the clutch member 725 and also carries the disk 726. When the roller 736 depresses the arm 737, the spindle 741 is moved downwardly against the pressure of the spring 727, thus separating the friction clutch member 725 from the clutch member 724, whereupon the spring 727 turns the disk 726 in the direction opposite to that indicated by the arrow in Fig. 7. A stop pin 742 fixed in the disk 726 limits the action of the spring 727 through engagement of said stop pin with a relatively stationary stop 743. As soon as the roller 736 has passed over the arm 737 the spring 727 moves the clutch member 725 into engagement with the constantly-rotating clutch member 724, whereupon the disk 726 begins rotating in the direction indicated by the arrow in Fig. 7. It will be understood that the reduction gearing is so proportioned that the lug 728 travels through its arc of movement while the carriage makes a complete round trip and awaits the lapse of the predetermined interval at the end thereof. Upon the termination of such interval the lug 728 acts to release the latch 715 and restart the carriage.

The time occupied by the lug 728 in disengaging the latch 715 depends upon the location of the stop pin 743. In order that the position of said stop pin may be conveniently altered when a change is made in the character of the yarn masses to be unwound, said stop pin is mounted upon a worm wheel 744, said worm wheel meshing with a worm 745 which is rigid with a knurled hand wheel 746. Herein, the worm wheel 744 forms the stationary part to which the spring 727 is fixed as hereinbefore stated.

I claim as my invention:

1. A winder having, in combination, a frame, and winder-tending mechanism mounted to travel in a circuit on said frame comprising a carriage, driving means for the carriage including a clutch, and means

actuated in the travel of the carriage to operate said clutch whereby to effect the stoppage of said mechanism at the end of each round trip. 65

2. A winder having, in combination, a frame, and winder-tending mechanism comprising a carriage arranged to travel in a circuit on said frame, driving means for the carriage including a continuously operating clutch element and a second clutch element normally engaging with the first clutch element, and means actuated in the travel of the carriage to disengage the second clutch element whereby to effect the stoppage of said mechanism at the end of each round trip. 70 75 80

3. A winder having, in combination, a frame, mechanism mounted to travel in a circuit on the frame including a carriage, driving mechanism for the carriage including a clutch, an element actuated in the travel of the carriage for operating the clutch to stop the travel of the carriage at the end of each round trip, and means acting to operate the clutch and set the carriage in motion after the lapse of a predetermined interval. 85 90

4. A winder comprising, in combination, a frame, mechanism including a carriage arranged to travel upon the frame, driving means for the carriage including a constantly rotating clutch element, a driven shaft, a spring controlled clutch element on said shaft normally engaging the first-mentioned clutch element, a normally stationary member carried by the frame, means including an element mounted on the carriage adapted to engage with said member in the travel of the carriage to actuate the movable clutch element against the action of its spring, and means acting after an interval of cessation of the travel of the carriage to release said member for movement whereby to permit of a re-engagement of said clutch elements. 95 100 105

5. A winder comprising, in combination, a frame, mechanism mounted to travel on the frame including a carriage, driving means for the carriage including a pair of clutch elements, and means for disengaging said clutch elements to stop the travel of the carriage comprising a rock shaft mounted on the carriage, a pair of arms mounted on said shaft, means carried by the carriage by which one of said arms is operatively connected with one of said clutch elements, and means carried by the frame arranged to contact with the other one of said arms in the travel of the carriage to rock said shaft whereby to effect a disengagement of the clutch elements. 110 115 120

3. A winder comprising, in combination, a frame, mechanism mounted to travel on the frame including a carriage, driving

means for the carriage including a pair of clutch elements, and means for disengaging said clutch elements to stop the travel of the carriage comprising a rock shaft mounted on the carriage, a pair of arms mounted on said shaft, means carried by the carriage by which one of said arms is operatively connected with one of said clutch elements, and means carried by the frame with which the other one of said arms is adapted to co-act to effect an oscillation of said shaft with an interval between its movements in opposite directions.

7. In a winder, the combination of a traveling carriage, means for causing the carriage to stop and after an interval restart including a controlling element for the driving means, a normally stationary abutment with which said element is adapted to engage in the travel of the carriage, and means operable to effect a movement of said abutment at a predetermined time out of the path of travel of said element.

8. In a winder having a frame, a carriage traveling on the frame, driving means for the carriage, and mechanism for stopping and restarting the carriage including a controlling element for the driving means, an abutment with which said element is adapted to co-act, and means for releasing said abutment for movement including a latch member, and means for intermittently actuating said latch member.

9. In a winder, the combination with a carriage having driving mechanism, of means for stopping and restarting the carriage including a controlling element and a member with which said element is adapted to co-act, said member having controlling means comprising a latch element normally holding the member against movement, a rotatable element operable in one direction to release said latch element, and spring means for actuating said rotary element in the opposite direction.

10. In a winder, the combination with a carriage having driving mechanism, of means for stopping and restarting the carriage including a controlling element and a member with which said element is adapted to coact, said member having controlling means comprising a latch element normally holding the member against movement, and an actuating element adapted to move through a predetermined arc of movement to effect a disengagement of the latch element after the lapse of an interval upon the stopping of the carriage.

11. In a winder, the combination with a carriage having driving mechanism, of controlling means for the carriage including a holding element, means operable to effect at a predetermined time a release of said element comprising a pivoted arm, an oscillatory member movable into engagement with said arm, and means for actuating said oscillatory member through a predetermined arc of movement in a period of time greater than that consumed in a complete trip of the carriage.

12. In a winder, the combination with a carriage having driving mechanism, of controlling means for the carriage including a holding element, means operable to effect at a predetermined time a release of said element comprising a pivoted arm, a rotary element having a part movable into engagement with said arm, means for actuating said rotary element in one direction including a clutch, and means operable in the movement of the carriage to disengage said clutch after the movement of said pivoted arm by the rotary element.

13. In a winder, the combination with a carriage having driving mechanism, of controlling means for the carriage including a holding element, means operable to effect at a predetermined time a release of said element comprising a pivoted arm, a rotary element having a part movable into engagement with said arm, means for actuating said rotary element in one direction including a clutch, means operable in the movement of the carriage to disengage said clutch after the movement of said pivoted arm by the rotary element, and means for resetting the rotary element for movement upon a re-engagement of the clutch in the continued travel of the carriage.

14. In a winder, the combination with a carriage having driving mechanism, of controlling means for the carriage including a holding element, means operable to effect at a predetermined time a release of said element comprising a pivoted arm, a rotary element having a part movable into engagement with said arm, means for actuating said rotary element in one direction including a clutch, means operable in the movement of the carriage to disengage said clutch after the movement of said pivoted arm by the rotary element, and means for adjusting the extent of movement of said rotary element.

15. In a winder, a frame, a winder-tending mechanism comprising a carriage arranged to travel on said frame, driving means for the carriage, and controlling means for said driving means adapted to stop and after an interval restart the carriage, said means comprising a holding member, and means for releasing said holding member comprising an actuating member, an oscillatory member arranged to operatively engage said actuating member, a continuously rotating element, and reduction gearing between said oscillatory element and said rotating element for effecting

2. movement of said oscillatory element whereby to effect an operation of said actuating element at the end of an interval of time following the stopping of the carriage.
3. In a winder, the combination with a traveling carriage, of a continuously operating motor mounted on the carriage to travel therewith, and driving mechanism actuated by said motor including mechanically operated means for automatically stopping the travel of the carriage while the motor continues to operate and restarting the carriage after the lapse of a predetermined interval.
4. In a winder, the combination with a frame and a carriage mounted to travel on the frame, of an electric motor mounted on the carriage, and driving mechanism including means operatively associated with the motor to normally cause the carriage to travel, and means associated with the frame with which the driving mechanism of the carriage is arranged to coact when the carriage reaches a predetermined position to stop the carriage and after the lapse of an interval of time restart it.
5. In a winder, the combination with a frame and a carriage arranged to travel on the frame, of a continuously operating motor mounted on the carriage, and mechanism carried by the frame and carriage arranged to coact when the carriage reaches a predetermined position to stop the carriage.
6. In a winder, the combination with a frame and a carriage mounted to travel on the frame, of a continuously operating motor mounted on the carriage, means arranged to be normally driven by the motor to cause the carriage to travel, and means on the frame with which said mechanism is arranged to coact to stop the travel of the carriage while the motor continues to operate.
7. In a winder, the combination with a frame, of a carriage arranged to travel on the frame, driving means for the carriage including a continuously operating motor, holding means arranged to prevent the carriage from traveling, and means operable to release said holding means after the lapse of a predetermined interval of time to effect the travel of the carriage.
8. A winder having, in combination, a frame, a carriage mounted to travel on the frame, driving means for the carriage including a continuously operating motor, holding means for preventing the travel of the carriage, and a continuously operating mechanism carried by the frame for automatically releasing the holding means and causing the driving means to act.
9. In a winder, the combination of a carriage arranged to travel, an electric motor, driving mechanism continuously operated by said motor, mechanism arranged to be driven to actuate the carriage, and means normally connecting said mechanisms to cause the carriage to travel and adapted to be automatically actuated in the movement of the carriage to disconnect said mechanisms to stop the travel of the carriage at a predetermined point in such travel.
10. In a winder, the combination of a carriage arranged to travel, an electric motor, continuously operating mechanism driven by said motor, mechanism arranged to be driven to actuate the carriage, and means normally connecting said mechanisms whereby the carriage is caused to travel and adapted to be automatically actuated in the travel of the carriage to disconnect said mechanisms to stop the travel of the carriage, said means also including mechanism operable after the lapse of a predetermined interval to restart the carriage.
11. A winder having a traveling carriage adapted to stop automatically, and mechanically-operated means for causing the carriage to resume its travel after an interval at rest.
12. A winder having a traveling carriage arranged to stop automatically, mechanically-operated means for causing the carriage to resume its travel after an interval at rest, and means for varying the duration of said interval.
13. In a winder, the combination of a traveling carriage and a mechanical controlling means therefor comprising a part to be actuated, a continuously operating drive means, a member having a normal operative connection with said drive means adapted to engage said part to move it, means for disconnecting said member from the driving means, and means for restoring said member to its initial position.
14. In a winder, the combination of a traveling carriage and a mechanical controlling means therefor comprising a part to be actuated, a continuously operating drive means, a member having a normal operative connection with said drive means adapted to engage said part to move it, means for disconnecting said member from the driving means, means for restoring said member to its initial position, and means for varying such initial position of the member.
15. The combination of a traveling carriage, a stop, a member adapted to engage said stop, means normally holding said stop stationary, and means operable to cause the last mentioned means to release the stop for movement by said member.
16. A winder having, in combination, a traveling carriage, winder-tending mechanism on the carriage, driving means normally having an operative connection with the carriage, and means operable automatically

cally at a predetermined point in the travel of the carriage to render said connection inoperative and thus stop the carriage.

30. A winder having, in combination a traveling carriage, winder-tending mechanism on the carriage, driving means, a connection between the carriage and the driving means, and means operable either man-

ually or automatically in the travel of the carriage to render such connection inoperative, said means being operable automatically at a predetermined point in the travel of the carriage. 10

In testimony whereof, I have hereunto set my hand.

HOWARD D. COLMAN.
